UNITED STATES PATENT OFFICE

170,560

MILLING MACHINE

Charles Tree, Racine, Wis.

Application February 14, 1952, Serial No. 18,518

Term of patent 14 years

(Cl. D54—14)

To all whom it may concern:

Be it known that I, Charles Tree, a citizen of the United States, residing at Racine, in the county of Racine and State of Wisconsin, have invented a new, original, and ornamental Design for a Milling Machine, of which the following is a specification, reference being had to the accompanying drawing, forming part hereof:

Figure 1 is a perspective view showing the front of the milling machine, embodying my new design.

Figure 2 is a perspective view showing the rear of the milling machine.

Figure 3 is a perspective view showing one side of the milling machine.

Figure 4 is a perspective view showing the other side of the milling machine.

I claim:

The ornamental design for a milling machine, as shown.

CHARLES TREE.
